[57] **CLAIM**

The ornamental design for an adjustable cosmetic applicator, as shown and described.

DESCRIPTION

FIG. 1 is a front elevational view of an adjustable cosmetic applicator showing our new design;

FIG. 2 is a side elevational view thereof;

FIG. 3 is an elevational view rotated 45% with the tip in an alternate position;

FIG. 4 is a top plan view thereof;

FIG. 5 is a bottom plan view thereof;

FIG. 6 is a top plan view of an adjustable cosmetic applicator showing a modified form of our new design;

FIG. 7 is a top plan view of an adjustable cosmetic applicator showing another modified form of our new design;

FIG. 8 is a side elevational view of the applicator of

FIG. 6; and

FIG. 9 is a side elevational view of the applicator in FIG. 7.
